UNITED STATES PATENT OFFICE.

ROLAND C. HILTON, OF BOSTON, MASSACHUSETTS, ASSIGNOR TO NATIONAL COUPLING MANUFACTURING COMPANY, OF BOSTON, MASSACHUSETTS, A CORPORATION OF MASSACHUSETTS.

HOSE-COUPLING.

1,071,921.

Specification of Letters Patent.

Patented Sept. 2, 1913.

Application filed August 23, 1912. Serial No. 716,635.

To all whom it may concern:

Be it known that I, ROLAND C. HILTON, a citizen of the United States, residing at Boston, county of Suffolk, State of Massachusetts, have invented an Improvement in Hose-Couplings, of which the following description, in connection with the accompanying drawing, is a specification, like characters on the drawing representing like parts.

10 This invention relates to hose couplings of that known type wherein one of the coupling members is provided with receding blocks having screw-threaded faces that are adapted to engage the screw-threads of the 15 other coupling member so that the two coupling members can be coupled by merely a longitudinal movement of one relative to the other.

20 The object of my invention is to provide a novel coupling of this type having the features which will be more fully hereinafter described and then pointed out in the appended claims.

25 Referring to the drawings wherein I have illustrated the preferred embodiment of my invention, Figure 1 is a sectional view of my improved coupling on the line $x-x$, Fig. 2; Fig. 2 is a section on the line $y-y$, Fig. 1; Fig. 3 is a fragmentary sectional view showing a different form of lock from that shown in Fig. 2; Fig. 4 is a fragmentary section on the line $a-a$, Fig. 1; Fig. 5 is a perspective view of the ring 7.

30 3 designates a coupling member having the exterior screw-threaded portion 4 adapted to screw into a female coupling member and also having provision for being coupled to a male coupling member 5. The coupling member 3 is provided with a plurality of receding blocks 6, each of which has screw-threads on its interior face adapted to engage the screw-threaded member 5, said blocks receding when the members are coupled to permit the quick coupling movement. 35 These receding blocks 6 are mounted in a ring 7 which is situated within the coupling 3, said ring being provided with radial apertures 8 in which the blocks slide back and forth. Each of the blocks 6 is 40 provided on its back with a notch or groove 9 in which is received a spring 10 that tends to force the blocks inwardly. Said spring can preferably be a coiled spring which encircles all of the blocks, although any other 45 yielding means for holding the blocks 6 for-

ward may be employed. The blocks 6 are longer than the thickness of the ring 7 so that the outer ends of the blocks project through the ring and occupy an annular recess 12 formed in the member 3. The projecting portion of each block 6 is provided with a beveled face 11 and the recess 12 is provided at one side with a specially-shaped face which co-operates with the beveled faces 11 in holding the receding blocks 6 to their work, as will be presently described. The ring 7 is capable of moving longitudinally within the coupling member 3, and when said ring is moved backwardly against the wall 14, then the blocks 6 are free to be 50 moved outwardly in a radial direction, while when the ring 7 is in its forward position, as shown in Fig. 1, and is held in such position the blocks 6 are locked in their operative position. The inward radial movement 55 of the blocks 6 is limited by a stop ring 15 which is situated within the ring 7 and is situated to be engaged by the blocks 6.

60 In coupling the member 3 to the male coupling member 5 the latter is inserted into the member 3 and when the screw-threads thereon engage the screw-threaded blocks 6, the ring 7 with the blocks therein will be carried backwardly against the wall 14. When the ring 7 has reached this position, 65 then during further entering movement of the male member 5 the blocks 6 will be forced backwardly against the action of the spring 10 and will click over the screw-threads of said member 5.

70 When the two members are coupled together and the screw-threaded faces of the blocks 6 engage and fit the screw-threads on the member 5, the blocks 6 occupy their inward position owing to the action of the spring 10 and the coupling is then tightened by simply giving the member 3 a partial turn. I have provided means whereby when the member 3 is thus given a partial turn the ring 7 will be forced toward the front, 75 thus bringing the blocks 6 into locking engagement with said member. The member 3 is shown as having one or more V-shaped projections 31 thereon and the ring 7 has complementary shaped recesses 32. The projections 31 and recesses 32 normally stand in line with each other and when the ring 7 is pushed backwardly during the time that the member 5 enters the member 3, the projections enter the recesses. When the cou- 80

110

pling has been forced onto the male member 5 as far as it can go and said member is given the partial turn the inclined faces of the projections 31 engage the inclined faces 5 of the recesses 32 and the camming action which results forces the ring 7 forwardly in the member 3.

The front face of the recess 12 is provided with two inclined portions 34, 35 separated 10 by the shoulder 36, and said shoulder is so positioned that when the ring 7 is forced forwardly into its locking position the ends of the blocks 6 will just engage the shoulder 36, as seen in Fig. 1. This shoulder 36 acts 15 as a means for locking the block 6 from backward rotation.

The ring 7 is an important feature of the invention for it causes all of the blocks 6 to move in unison in an axial direction as 20 the male member 5 is entered into the coupling. This insures that all of the blocks will be operative in effecting the coupling.

It will be noted that the ring 7 has a diameter equal to the interior diameter of 25 the chamber in the end of the coupling member 3. In assembling the parts the blocks 6 are first mounted in the ring but located therein so that the outer ends of the blocks do not project beyond the periphery of the ring and then said ring with 30 the blocks therein is slipped into the coupling member 3. The blocks 6 are then forced outwardly into the position shown in Fig. 1 and the stop ring 15 is put in place. The outer projecting ends of the blocks 6 35 serve to prevent the ring 7 from being withdrawn from the coupling, and the ring 7 holds all of the blocks in alinement and insures that they will all act simultaneously 40 during the coupling operation.

My invention also includes a lock to hold 45 positively the ring 7 in its forward position when the two coupling members are coupled together, thus locking positively the blocks 6 in their operative position. In Fig. 2 this 50 lock is shown as a locking lever 20 pivoted at 21 and provided with a locking lip 22 that is adapted to enter behind the ring 7 between the latter and the wall 14. This 55 locking lever 20 is shown as having an extension 23 which extends through the periphery of the member 3 and provides a thumb-piece by which it can be thrown out of operative position. 24 is a spring for normally holding the locking lever in its operative position.

In Fig. 3 I have shown another embodiment of the invention wherein the locking member is in the form of a push-button 60 45 which plays in a radial aperture in the member 3. The push-button is normally held in its operative position by means of a spring 46, and when in such position the portion 37 thereof is situated between the 65 ring 7 and the wall 14, thus locking the ring

in its forward position. This push-button is provided with a notch 28 which is brought into alinement with the ring 7 when the push-button is depressed, and when the parts are in this position the ring 7 is permitted to move rearwardly against the wall 14. The ring 7 is shown as provided with a notch or recess 41 to receive the portion 37 of the push button when the latter is depressed and the ring is forced rearwardly. 70

In coupling the two members together the operator depresses the push button so as to release the lock, thus permitting the ring 7 to have its rearward movement as above described. When the members are coupled 80 together, then the push button is released and the lock is moved into an operative position thereby locking the ring 7 in its forward position.

Having fully described my invention what 85 I claim as new and desire to secure by Letters Patent is:—

1. In a coupling member, the combination with a body having in one end thereof a chamber provided with a recess in its exterior wall, of a ring within said chamber, said ring being of a size to permit it to be inserted axially into said chamber and being provided with radial apertures, and blocks mounted in said apertures for radial 90 movement, said blocks having their inner faces provided with screw-threads and having a greater length in a radial direction than the thickness of the ring whereby the outer ends of the blocks project through the 95 ring and prevent the latter from being withdrawn. 100

2. In a coupling member, the combination with a body having in one end thereof a chamber provided with a recess in its exterior wall, of a ring within said chamber, said ring being of a size to permit it to be inserted axially into said chamber and being provided with radial apertures, blocks mounted in said apertures for radial movement, said blocks having their inner faces provided with screw-threads and having a greater length in a radial direction than the thickness of the ring whereby the outer ends of the blocks project through the ring and 110 prevent the latter from being withdrawn, and means associated with the ring to limit the inward movement of the blocks. 115

3. In a coupling member, the combination with a body having in one end thereof a chamber provided with a recess in its exterior wall, of a ring within said chamber, said ring being of a size to permit it to be inserted axially into said chamber and being provided with radial apertures, and blocks 120 mounted in said apertures for radial movement, said blocks having their inner faces provided with screw-threads and having a greater length in a radial direction than the thickness of the ring whereby the outer ends 125 of the blocks project through the ring and 130 prevent the latter from being withdrawn.

of the blocks project through the ring and prevent the latter from being withdrawn, said ring being capable of movement relative to the body in the direction of its axis, 5 and means for locking the ring in its forward position.

4. In a female coupling member, the combination with a body, of a ring situated within the body and provided with radial 10 apertures, said ring being capable of movement relative to the body in the direction of its axis, blocks mounted in said apertures for radial movement and provided on their inner faces with screw-threads to engage 15 those of a coöperating male member, and means for locking the blocks in their inward operative position when the ring is in its forward position while permitting said blocks to freely move radially when the 20 ring is in its rearward position, said ring causing all the blocks to have a simultaneous movement in an axial direction.

5. In a female coupling member, the combination with a body, of a ring situated 25 within the body and capable of movement relative thereto in the direction of its axis and provided with radial apertures, blocks mounted in said apertures for radial movement and provided on their inner faces with 30 screw-threads to engage those of a coöperating male member, means for locking the blocks in their inward operative position when the ring is in its forward position while permitting said blocks to freely move 35 radially when the ring is in its rearward position, and means to lock the ring in its forward position.

6. In a female coupling member, the combination with a body, of a ring situated 40 within the body and capable of movement relative thereto in the direction of its axis and provided with radial apertures, blocks mounted in said apertures for radial movement and provided on their inner faces with 45 screw-threads to engage those of a coöperating male member, means for locking the blocks in their inward operative position when the ring is in its forward position while permitting said blocks to freely move 50 radially when the ring is in its rearward position, and a manually-controlled lock to hold the ring in its forward position.

7. In a female coupling member, the combination with a body, of a ring mounted in

the body for movement relative thereto in 55 the direction of its axis and provided with radial apertures, said body having an annular recess exterior to the ring and provided with an inclined wall, receding blocks occupying said apertures and having screw- 60 threads on their inner faces to engage exterior threads on their inner faces to engage 65 exterior screw-threads of a coöperating male member, said blocks extending through the ring into said annular recess and being provided with inclined faces to co- 70 operate with the inclined wall of the recess to hold the blocks in their operative position when the ring is in its forward position, said annular recess permitting the blocks to 75 move outwardly in their apertures when the ring is in its backward position.

8. In a female coupling member, the combination with a body, of a ring mounted in the body for movement relative thereto in 75 the direction of its axis and provided with radial apertures, said body having an annular recess exterior to the ring, receding blocks in the ring having their inner ends projecting beyond the interior face of the 80 ring and provided with screw-threads to engage the screw-threads of a coöperating male member, the outer ends of said blocks projecting beyond the exterior of the ring and occupying said recess whereby move- 85 ment of the ring forwardly in the body is limited by the engagement of the blocks with the walls of the recess.

9. In a female coupling member, the combination with a body, of a ring mounted in 90 the body for movement relative thereto in the direction of its axis and provided with radial apertures, blocks mounted in said apertures for radial movement and provided on their inner faces with screw-threads to 95 engage those of a coöperating male member, and cam means between said ring and coupling member by which the ring is forced forwardly when the coupling member is turned relative thereto.

In testimony whereof, I have signed my name to this specification, in the presence of two subscribing witnesses.

ROLAND C. HILTON.

LOUIS C. SMITH.

It is hereby certified that in Letters Patent No. 1,071,921, granted September 2, 1913, upon the application of Roland C. Hilton, of Boston, Massachusetts, for an improvement in "Hose-Couplings," an error appears in the printed specification requiring correction as follows: Page 3, strike out line 61; and that the said Letters Patent should be read with this correction therein that the same may conform to the record of the case in the Patent Office.

Signed and sealed this 7th day of October, A. D., 1913.

[SEAL.]

R. T. FRAZIER,

Acting Commissioner of Patents.
